UNITED STATES PATENT OFFICE.

KARL G. BAREIS, OF MACFARLAND, WISCONSIN.

BAND-CUTTER AND FEEDER.

SPECIFICATION forming part of Letters Patent No. 379,355, dated March 13, 1888.

Application filed January 4, 1887. Serial No. 223,389. (No model.)

To all whom it may concern:

Be it known that I, KARL GEORGE BAREIS, of MacFarland, in the county of Dane and the State of Wisconsin, have invented a new and 5 Improved Band-Cutter and Feeder for Thrashing-Machines, of which the following is a full, clear, and exact description.

The object of my invention is to provide a new and improved device for cutting the bands 10 of sheaves and feeding the loose grain to the thrashing-cylinder of a thrashing-machine.

The invention consists of various parts and 15 details and combinations of the same, as will be fully described hereinafter, and then pointed out in the claims.

Reference is to be had to the accompanying 20 drawings, forming a part of this specification, in which similar letters of reference indicate corresponding parts in all the figures.

Figure 1 is a plan view of my improvement. Fig. 2 is a longitudinal sectional elevation of 25 the same on the line *x x* of Fig. 1. Fig. 3 is a side elevation of the same. Fig. 4 is an end elevation of the same, with parts in section.

The thrashing-machine A is provided with 30 the usual thrashing-cylinder, B, mounted on the shaft B', carrying on one end the gear-wheel B², which meshes into the gear-wheel B³, attached to the shaft C, mounted in suitable 35 bearings on the frame D, extending from and secured to one end of the thrashing-machine A. The frame D is of suitable construction, and carries the several devices constituting my improvement.

On the shaft C is secured the roller C², over 40 which passes the endless belt E, which leads the loose grain to the thrashing-cylinder B and passes over the loose rollers F and F', suitably mounted on the frame D. Above the 45 roller F is placed the grooved roller G, which is held in bearings H and adapted to slide up and down between the standards D', erected on the frame D, and each of the bearings H is connected by an adjustable link, I, with the lever I', on the front end of which is adjustably held the link I², carrying on its lower end the feed-bar J, which extends from side to side of the frame D and is guided in the same, and is also held in front of the grooved 50 roller K. Below the latter is placed a roller, L, over which passes the endless slat belt M, which reaches to the front end of the frame D,

and also passes over the roller N. The links I I² are made adjustable so as to increase or diminish the space between the feed-bar J and the slat belt M and to regulate the space 55 between the rollers F and G. The bearings H are each held in a downward position by a spring, H', resting with one end on the top of the said bearings H, and its other end bearing 60 against the plate H², extending from side to side of the frame, and on the top of which press the screws H², passing through the horizontal beams D³ of the frame D. By operating the screws H² the tension of the springs 65 H' and the consequent pressure of the roller G may be regulated.

The roller K is secured on the shaft K', on one end of which is keyed or splined the sliding gear-wheel K², which meshes into the gear-wheel L², secured on the shaft L', carrying 70 the roller L. The gear-wheel K² is provided with a collar, K³, on which operates the forked lever K⁴, fulcrumed on the frame D and serving to move the said gear-wheel K² into 75 or out of engagement with the said gear-wheel L², thereby preventing grain being fed to the cylinder when it is not in motion, as said gears must first mesh in order that the primary belt M of the carrier mechanism may operate. 80 On the other end of the shaft K' is placed a pulley, P, over which passes an endless belt, Q, which also passes under the pulley G², attached to the shaft G', carrying the grooved roller G, and around the pulley C³, secured to 85 the shaft C. The rotation of the latter imparts motion, by means of the said belt Q, to the rollers G and K, and the latter imparts a traveling motion to the slat belt M by means of the gear-wheels K² and L².

A belt-tightening device, R, is connected with the belt Q, so as to take up any slack of said belt caused by the rising of the grooved roller G and its pulley G². This tightening device R consists of a roller, S, bearing against 90 the inside surface of the belt Q and mounted to rotate on a stud, s, secured to an arm, T, pivoted on the segmental arm U and connected with the spring T', having one end secured to the said arm T and its other end to 95 a pin, t, on the said segmental arm U. The latter is provided with an inwardly-projecting lug, U', which fits into any one of a series of corresponding recesses in the plate U², secured to 100

the side of the frame D. The plate U swings on the same stud as the arm T.

A series of knives, V, is arranged across the slat belt M, and said knives are secured to the 5 rock-shaft V', extending across the frame D and mounted on each side in bearings V², sliding between guides on the top of the side beam of the frame D.

The knives are adjustable on the rock-shaft 10 V' toward and from the slatted belt M by means of the clamps v on their upper ends. Each clamp is made in two sections, one section, v', being formed on the upper part of a knife and the other part, v², being hinged to the section v', as shown at v³, a set-screw, v⁴, serving to adjust the two sections securely upon the said shaft V'. On the rear end of each of the 15 bearings V' is held the upright rod V⁵, on which slides one end of the arm V⁶, which has its other end secured to the cross-shaft V'. On 20 the rod V⁵ is a coiled spring, V⁶, resting with one end on the said arm V⁶, and its other end bears against a nut, V⁷, screwed on the upper end of the said rod V⁵. This arrangement 25 holds the knives in a yielding position in relation to the slat belt M, so that the knives adjust themselves according to the amount of grain on the said belt.

Each of the bearings V² is provided with 30 an extension, V⁸, having on its upper surface rack-teeth in which mesh the teeth of a pinion, W, secured to the shaft W', mounted in suitable standards erected on the side beams of the frame D. The shaft W' can be turned 35 by a crank-arm or other suitable means, so as to cause the shaft V' and the knives V to move toward and from the front end of the frame D. A pivoted locking-arm, W², prevents the pinion W from turning when thrown in gear, as 40 shown in Fig 2. By thus movably mounting the knives they may be readily adjusted to suit bundles of different lengths.

The operation is as follows: The rotation of the thrashing-cylinder B imparts motion to 45 the endless belt E, the grooved rollers G and K, and the slat belt M, in the direction indicated by the arrows in Fig. 2. The two said belts E and M therefore form what may be generically termed the "carrier" or "carrier 50 mechanism." The sheaves are thrown upon the front end of the slat belt M, which carries them forward and under the knives V, which cut the bands, and the loose grain is then passed by the slat belt M under the feed-bar J 55 and to the grooved roller K, which presses the grain downward and upon the endless belt E, which carries the grain to and under the grooved roller G, which rises and falls according to the amount of grain carried forward by 60 the said belt E. The upward and downward motion of the grooved roller G imparts an up-and-down motion to the feed-bar J, which thus prevents too much grain from passing to the grooved roller K. The passage of the 65 grain is, however, continuous, as the movement of the belt M of the carrier mechanism is not interfered with by the up-and-down

movement of the feed-bar, said bar descending only far enough to lessen the amount of grain passing under it until the choke is relieved. The grain, after leaving the grooved roller G, is carried by the endless belt E to the cylinder B of the thrashing-machine. 70

It will be seen that when the roller G rises the belt Q will become slack, but the slack is 75 taken up by the roller S, mounted on the arm T, which swings downward, this motion being caused by the action of the spring T' on said arm T. The tension of the roller S on the belt Q can be adjusted by means of the pivoted 80 arm U, which can be moved up or down and locked in position by its arm U' engaging one of the recesses in the plate U².

When the machine is to be stopped, the operator can stop the movement of the slat belt, 85 and consequently the feed, by throwing the gear-wheel K² out of contact with the gear-wheel L' by means of the forked lever K⁴, so that no more grain can pass to the thrashing-cylinder when the latter is slackening up its 90 speed.

Having thus fully described my invention, I claim as new and desire to secure by Letters Patent—

1. The combination, with the carrier mechanism, consisting of endless slat belt M and endless belt E, of the vertically-movable feed-bar above the belt M, the vertically-movable feed-roller above the belt and in rear of the feed-bar, and connections between the said feed bar and roller, whereby when the feed-roller is raised the feed-bar will be depressed, substantially as set forth. 95

2. The combination, with the endless-carrier mechanism, consisting of the endless slat belt M and the endless belt E, of the vertically-movable feed-bar, a vertically-movable feed-roller, and a lever pivoted between its ends to the frame and in connection at its ends with the feed bar and roller, whereby upward movement of the roller will force the feed-bar downward into the path of the grain, substantially as set forth. 105 110

3. The combination, with the endless belt and an intermediate roller over which the upper part of the belt passes, of the grooved feed-roller mounted in vertically-movable bearings above said intermediate roller, the endless slat belt above the first-named belt in front of the feed-rollers and delivering thereto, the vertically-movable feed-bar above the forward end of the slat belt, and connections between said bar and grooved feed-roller for depressing the former when the latter is raised, substantially 115 120 as set forth. 125

4. In a band-cutter and feeder for thrashing-machines, the endless belt E and the endless slat belt M, in combination with the grooved roller G, mounted in the bearings H, the springs H', operating on the said bearings, the links I, connected with the said bearings H, the levers I', connected with the said links, the links I², connected with the front end of the levers I', and the feed-bar J, hung on the said links 130

I² above the said slat belt M, substantially as shown and described.

5. The combination, with the frame, the carrier mechanism comprising the two belts, their rollers, one of which has a pulley, the feed-roller and its pulley, and the feed-bar operated from said feed-roller, of the belt driving the feed-roller pulley, an adjustable arm connected to the frame, a second arm pivoted upon the first-named arm and having a pulley bearing against the driving-belt to take up slack when the feed-roller rises, and a spring forcing the two said arms apart and thereby holding the pulley against the belt, substantially as set forth.

6. The combination, in a feeder for thrashing-machines, with the vertically-adjustable feed-roller, the belt driving the same, and the frame D, of a plate, U², secured to said frame and having recesses, the arm U, having an inwardly-projecting lug, U', engaging one of said recesses, and the outward-projecting pin, the arm T, the pulley secured thereon and bearing against the inner surface of the belt, and the spring T', bearing against the arm T, and the outward-projecting pin, substantially as set forth.

7. In a band-cutter and feeder for thrashing-machines, the grooved roller G, the bearings H, supporting the said roller G, the springs H', pressing on the said bearings H, the adjustable cross-plate H³, pressing on the said springs H', the links I, supporting the said bearings H, and the levers I', pivotally connected with the said links I, in combination with the links I², pivoted on the said levers I', and the feed-bar J, held on the lower ends of the said links I², substantially as shown and described.

8. In a band-cutter and feeder for thrashing-machines, the grooved roller G, the bearings H, supporting the said roller G, the springs

H', pressing on the said bearings, the cross-plate H³, pressing on the said springs, the screws H², for adjusting the said plate H³, the links I, supporting the said bearings H, and the levers I', pivotally connected with the said links, in combination with the links I², pivoted on the levers I', and the feed-bar J, held on the lower ends of the said links, substantially as shown and described.

9. The combination, in a band-cutter and feeder, with the carrier, of the band-cutting knives above the carrier, and longitudinally-adjustable bearings for said knives, whereby the knives may be adjusted for bundles of different lengths, substantially as set forth.

10. In a band-cutter and feeder, a rock-shaft having a spring-tension, and knives secured adjustably to said shaft, whereby the knives may be set at any desired angle and also allowed to yield, substantially as set forth.

11. In a band-cutter, the combination, with the rock-shaft, bearings therefor, and the knives on the rock-shaft, of an arm secured to the shaft, a rod extending through the outer end of said arm, and a spiral spring surrounding the rod and bearing on said arm, substantially as set forth.

12. The combination, with the frame, of the slat belt M and its rollers L N, the lower belt, E, and its rollers F' F C², the feed-roller G, driven from the roller C², the feed-bar J, connected with and operated from the feed-roller, the intermediate roller, K, driven from the roller C², the gearing connecting the said roller K with the belt-roller M, and means for disconnecting the said gearing, substantially as set forth.

KARL G. BAREIS.
